CLAIM

The ornamental design for a under cabinet light, as shown and described.

DESCRIPTION

FIG. 1 is a perspective view of an under cabinet light;
FIG. 2 is an alternative perspective view of the under cabinet
light of FIG. 1;

FIG. 3 is a front view of the under cabinet light of FIG. 1;
FIG. 4 is a rear view of the under cabinet light of FIG. 1;
FIG. 5 is an elevational view of the under cabinet light of
FIG. 1;

FIG. 6 is a bottom view of the under cabinet light of FIG. 1;
FIG. 7 is a side view of the under cabinet light of FIG. 1;
and,

FIG. 8 is an opposite side view of the under cabinet light of
FIG. 1.

It should be appreciated that the broken lines are merely
illustrative of the environment of the design, and not part of
the claimed design.
